(57) **CLAIM**

The ornamental design for a front combination lamp for an automobile, as shown and described.

DESCRIPTION

FIG. 1 is a front side perspective view of a front combination lamp for an automobile in accordance with a first embodiment of my new design.

FIG. 2 is a front elevational view thereof;

FIG. 3 is a rear elevational view top plan view thereof;

FIG. 4 is a top plan view thereof;

FIG. 5 is a bottom plan view thereof; and,

FIG. 6 is a left side elevational view thereof.

The front combination lamp is configured to be mounted to an automobile. The mounting structure and support structure of the front combination lamp, enclosed by broken lines in FIGS. 1 to 6, form no part of the claimed design since the mounting structure and support structure are hidden when the front combination lamp is mounted to the automobile. In addition, the appearance of the rear side and inside structures of the front combination lamp as shown in broken lines in FIGS. 1 to 6 is for purpose of illustrating the boundaries of the exterior surface of the front combination lamp, and forms no part of the claimed design. The front combination lamp has a front lens that is transparent such that features behind the lens are at least partially visible as illustrated.

A second embodiment of my new design includes the mirror image of the front combination lamp shown in FIGS. 1 to 6.

1 Claim, 6 Drawing Sheets
